UNITED STATES PATENT OFFICE.

SAMUEL K. DENNIS, OF CHICAGO, ILLINOIS, ASSIGNOR TO THE PLANO MANUFACTURING COMPANY, OF SAME PLACE.

DESIGN FOR A SEAT FOR FARMING MACHINERY.

SPECIFICATION forming part of Design No. 34,004, dated January 29, 1901.

Application filed January 5, 1901. Serial No. 42,253. Term of patent 14 years.

To all whom it may concern:

Be it known that I, SAMUEL K. DENNIS, a citizen of the United States, residing at Chicago, in the county of Cook and State of Illinois, have invented and produced a new and original Design for Seats for Farming Machinery, of which the following is a specification, reference being had to the accompanying drawings, forming a part thereof.

10 Figure 1 is a perspective view of a seat, showing my new design. Fig. 2 is a plan view of the same, and Fig. 3 is a sectional view on the line A A of Fig. 2.

15 As shown in the drawings, the leading or material feature of my design consists of the configuration of the central depressed portion a of the seat.

20 The outer portion of the seat is of the generally concave shape shown, with the depressed portions b and c at the front separated by the convex pommel or horn d, and has its sides and rear terminating in the downwardly-turned flange e.

25 The circular central portion a is depressed slightly below the outer portion of the seat, the boundary thereof forming the offset f. Just within the central portion are the depressed ribs g, equidistant from the center, but parallel to a line running from the front to

the rear of the seat and extending below the 30 surface of the central portion a. Concentric with said circular central portion a and a little inside of the inner edges of the ribs g is the raised annular rib h, projecting above said central portion a. Extending radially 35 from and forming continuations of the rib h are the raised ribs j, whose lengths are determined by the boundary necessarily formed by the ribs g and the offset f. In the center of the central portion a is the square aperture k.

As seen in Fig. 3, the thickness of the seat is substantially uniform throughout, so that the raised ribs on one side produce corresponding depressions on the other side, and 45 vice versa.

Having described my invention, what I claim as new, and desire to secure by Letters Patent of the United States, is—

The design for a seat for farming machinery, as herein shown and described.

In testimony whereof I have signed my name to this specification in the presence of two subscribing witnesses.

SAMUEL K. DENNIS.
